Primary Examiner — Angela J Lee

(57) **CLAIM**

I claim the design for a bracket mount for electronic tablet device, as shown and described.

DESCRIPTION

FIG. 1 is an elevation view of the front of the bracket mount for electronic tablet device;

FIG. 2 is a right side elevation view thereof;

FIG. 3 is a left side elevation view thereof;

FIG. 4 is a longitudinal sectional view thereof;

FIG. 5 is a transverse sectional view thereof; and,

FIG. 6 is an isometric view thereof.

The broken line appearing within the figures indicates the vertical surface to which the bracket mount is attached. This vertical surface is shown for illustrative purposes only and is not part of the design.
